UNITED STATES PATENT OFFICE.

RALPH W. HUTCHENS, OF EAU CLAIRE, WISCONSIN, ASSIGNOR TO GILLETTE RUBBER COMPANY, OF EAU CLAIRE, WISCONSIN, A CORPORATION OF WISCONSIN.

DESIGN FOR A TIRE OR SIMILAR ARTICLE.

Application filed September 20, 1923. Serial No. 7,274. Term of patent 7 years.

To all whom it may concern:

Be it known that I, RALPH W. HUTCHENS, a citizen of the United States, residing at Eau Claire, Eau Claire County, Wisconsin, have invented a new, original, and ornamental Design for a Tire or Similar Article, of which the following is a specification, reference being had to the accompanying drawing, forming part thereof.

On the drawing:

I claim:

The ornamental design for a tire or similar article as shown.

RALPH W. HUTCHENS.
